UNITED STATES PATENT OFFICE.

RUTH A. GILCHRIST, OF PHILADELPHIA, PENNSYLVANIA.

DESIGN FOR A COVER FOR PRESERVE-JARS.

SPECIFICATION forming part of Design No. 34,168, dated March 5, 1901.

Application filed January 19, 1900. Serial No. 2,075. Term of patent 14 years.

To all whom it may concern:

Be it known that I, RUTH A. GILCHRIST, a citizen of the United States, residing at Philadelphia, in the county of Philadelphia and State of Pennsylvania, have invented and produced a new and original Design for Covers for Preserve-Jars; and I do hereby declare the following to be a full, clear, and exact description of the same, reference being had to the accompanying drawings, forming a part thereof.

In the accompanying drawings, Figure 1 is a perspective view of the cover embodying my design looking at the same from above. Fig. 2 is a similar view embodying my design looking at the cover from beneath, and Fig. 3 is a vertical transverse section through the cover embodying my design.

The leading feature of my design consists of a cover having a vertical flange portion, the cover being concaved on top, forming an inverted pendent portion, and a horizontal

portion connecting the vertical flange to the pendent portion.

A in the drawings represents my cover, which is formed with a vertical flange a and is concaved on top, as at a' , to form an inverted pendent portion a^2 . The upper edge of the pendent portion is connected to the upper edge of the vertical flange portion by a horizontal connecting portion a^3 , which forms an annular chamber a^4 all around the pendent portion.

Having now described my invention, what I claim as new, and desire to secure by Letters Patent, is—

The design for a cover for a preserve-jar substantially as herein shown and described.

In testimony whereof I hereunto affix my signature in presence of two witnesses.

RUTH A. GILCHRIST.
